UNITED STATES PATENT OFFICE

HOY OWEN, OF LUFKIN, TEXAS

VIBRATING DOFFER FOR COTTON GINS

Application filed September 30, 1929. Serial No. 396,111.

My invention relates to cotton gins and more particularly to a doffer designed to more effectively deliver the cotton to the gin saws.

5 In the ginning of cotton difficulty is experienced with the ordinary type of cotton gin in a construction of means for delivering the cotton to the saws of the gin in such manner that it may be most effectively engaged 10 by the gin saws and the lint thereby separated from the seed.

The gin saws rotate the roll of seed cotton above them and as this roll of cotton comes in contact with the teeth of the saws the lint is 15 engaged by the saw teeth and it is stripped free of the seed. The effectiveness of the ginning operation depends to a great extent upon how well the roll of cotton is rotated. As the roll is ordinarily dependent upon the engagement therewith of the saws for its rotation, it is not always possible to obtain satisfactory results. This is particularly true 20 where the rotating disc is employed to co-act with the saws to gin the cotton. When the 25 cotton roll is not rotated properly the friction of the saws may cause fire in the cotton.

It is the object of my invention to provide a doffer located in a position above the gin saws and mounted to assist in bringing in the 30 cotton into the proper position for ginning and to assist in imparting a rotating movement to the cotton roll.

I desire to prevent the passage of the cotton away from the saws and at the same time to 35 move the cotton downwardly where it may be brought into a most effective position for ginning, at the same time assuring that the cotton cannot pack about the saws.

In the drawing herewith, Figure 1 is a 40 broken sectional view through the housing of the cotton gin and showing the manner of mounting of my improved doffer. Figure 2 is a fragmental view in vertical section on the plane 2-2 of Figure 1.

45 Figure 3 is a broken view similar to Figure 1 but illustrating a slightly different embodiment of the invention.

Figure 4 is a transverse section on the plane

4-4 of Figure 3.

50 It is to be understood that my invention is

adapted to be used with cotton gins of any ordinary type of construction. I have therefore illustrated only such portions of the gin as are necessary for a correct understanding of my improved doffer.

55 In the drawing the gin saws 1 are shown in broken detail illustrating the upper edges of said saws and it is to be understood that these saws are mounted upon a shaft or roller 2 of ordinary construction and are rotatable in the direction of the arrow.

60 The cotton is understood as being fed in above the rotating saw blades; and directly above said saws, and preferably a little to the rear of the axis of the saws is a shaft 3, supported for rotation in bearing 4, upon the side walls 5 of the housing. Upon this shaft 65 are a series of disc shaped rolls 6. With reference to Figure 1 it will be seen that these discs are spaced apart upon shaft 3, to provide a space indicated at 7 between the said discs to receive the saw blades 1. Thus when the cotton is fed to the upper side of the saws the discs 6 roll between the adjacent blades of the gin saws and bring the cotton into an effective contact with the saw blades and assist in separating the lint from the seed.

70 Above the shaft 3 is my improved doffer. It comprises a plate 8 which extends the full width of the gin above the disc 6. It is of 75 material thickness as will be seen from Figure 2, and is preferably arcuate in end view. It is of slightly thinner cross section at its upper edge and is there secured to a rod or 80 shaft 9. Said connection is a hinged connection as will be noted from Figure 1. The rod 9 is supported upon a short plate 10 connected with a supporting rod or shaft 11 at its upper end.

85 It will be seen from Figure 1 that the rod 11 is supported at its ends in the side walls of the housing. The plate 10 is short enough to move freely between the sides of the housing and has a pivotal connection at its lower end with rod 9. Thus the plate 10 may have a slight swinging movement with rod 11 as indicated in dotted lines in Figure 2.

90 The lower end of the doffer is wider and has its end concaved on the arc of the discs

6. The forward face of the doffer may be corrugated as shown in Figure 2 to better engage and move the cotton roll. The doffer is separated from the discs by a short distance and is adapted to be moved relative to the discs by means of an eccentric 12 secured upon a shaft 13. It is to be understood that there are two eccentrics 12 shown in dotted lines on Figure 1, mounted upon the shaft 13 and rotatable within an opening 14 longitudinally through the doffer plate. The shaft 13 is rotatable through a sprocket wheel 15, mounted thereon, and moved from any desired source of power.

15. When the gin is in operation the doffer will be given oscillating movement relative to the adjacent discs 6. This oscillating movement is indicated by the dotted lines in Figure 2. The doffer will be raised slightly and moved to the rear somewhat and then brought downwardly towards the disc and moved forwardly. In this manner the seed cotton fed towards the gin saws will be moved downwardly and forwardly so as to be engaged by the disc 6 and carried more effectively against the saws and as the roll of cotton is moved by the doffer, it is given a rotative movement in the right direction as will be clear from the arrow. It will be seen that the movement of the doffer 8 will be given some freedom at its upper end also through the swinging movement allowed at the upper end through attachment to the swinging plate 10. This doffer provides a most effective barrier against the passage of seed cotton away from the saws and also assists in moving the cotton into the proper position where it may be acted upon by the gin. It prevents clogging of the cotton roll, assists in its rotation, and thus avoids danger of fire.

45. In Figures 3 and 4 I have shown a slightly different arrangement of a doffer. In this embodiment the doffer 8a is pivoted upon a stationary rod 16 at its upper end and swings upon said rod as a pivot. The doffer is of comparatively the same shape as in the previous embodiment, being given an agitating movement by a somewhat different mechanism. A rod or shaft 17 extends longitudinally through the lower end of the doffer and a pair of swinging arms 18 are secured to said rod adjacent the end of said rod as will be seen in Figure 3. The arms 18 form a connection between the rod 17 and an eccentric 19 mounted upon an adjacent shaft 20, supported in the housing. It will be seen from Figure 4 that when the shaft 20 is rotated the eccentric thereon will communicate a reciprocating movement through the arm or pitman 18 thus moving the rod 17 and the doffer back and forth from the full line position to the dotted line position in Figure 4.

65. This embodiment is quite similar to that

shown in Figure 1. It is of slightly cheaper construction and its action is slightly different in that it is not so flexible as is the doffer shown in the first embodiment. This is due to the fixed mounting of the upper end of the doffer plate.

70. By the use of the doffer as shown and described the cotton is prevented from passing the gin saws without being properly acted upon by the saws and the action of the doffer assists materially in moving the cotton into position where it may be more easily acted upon by the gin saws and prevents the accumulation of cotton at the upper side of the gin housing. The agitating movement imparted to the cotton roll prevents clogging of the roll against the saws and assists in its free rotation, whereby the best ginning action is obtained. The advantage of this construction will be understood by those skilled in the art.

75. Having thus described my invention what I claim as new and desire to protect by Letters Patent is:

1. In a cotton machine including rotating saws and means to move cotton into contact with said saws, the combination of a doffer adjacent said means comprising a plate transversely of the machine, said plate being pivoted at its upper end, and means adjacent the lower end of said plate to give said doffer a reciprocating motion.

80. 2. In a cotton machine including rotating saws and means to move cotton into contact with said saws, the combination of a doffer adjacent said means comprising a plate transversely of the machine and concaved on its forward side, said plate being pivoted at its upper end, and means adjacent the lower end of said plate to give said doffer a reciprocating motion.

85. 3. In a cotton machine including rotating saws and means to move cotton into contact with said saws, the combination of a doffer adjacent said means comprising a plate transversely of the machine, said plate being pivoted at its upper end, and means to give said doffer a reciprocating motion.

90. 4. In a cotton machine including rotating saws and means to move cotton into contact with said saws, the combination of a doffer adjacent said means comprising a plate transversely of the machine and concaved on its forward side, said plate being pivoted at its upper end, and means to give said doffer a reciprocating motion.

95. 5. In combination with a cotton gin having gin saws therein, rotating discs inter-fitting between said saws, a doffer above said discs including a plate concaved on its forward side and pivoted at its upper end, and a rotating shaft operatively connected with said plate to give said plate a downward and forward movement.

100. 6. In combination with a cotton gin having

gin saws therein, rotating discs inter-fitting between said saws, a doffer above said discs including a plate concaved on its forward side and pivoted at its upper end, and a rotat-
5 ing shaft operatively connected with said plate to impart an agitation to said plate.

7. In a cotton machine having rotating saws, means to move the cotton into contact with said saws, and a doffer plate pivoted above said saws and having its lower end adjacent said cotton moving means, and means to reciprocate said plate.

8. In a cotton machine having rotating saws, means to move the cotton into contact with said saws, and a doffer plate pivoted above said saws and having its lower end adjacent said cotton moving means, and a rotatable shaft adjacent the lower end of said plate and operative connections between said 23 plate and said shaft whereby said plate is oscillated to move the cotton toward said means.

9. In a cotton machine having rotating saws therein and means to move the cotton toward said saws, the combination of a doffer blade above said means, means to pivotally support the upper edge of said blade to allow a swinging movement thereof, a rotatable shaft, an eccentric thereon, and operative 25 connections between said eccentric and said doffer blade to impart an oscillating movement to said blade.

10. A cotton gin including a series of gin saw blades, discs rotatable between said 35 blades to move the cotton thereto, in combination with a doffer blade above said discs and having its upper end curved forwardly and connected to a pivotal support, and means to move said blade forwardly and down-
40 wardly.

11. A cotton gin including a series of gin saw blades, discs rotatable between said blades to move the cotton thereto, in combination with a doffer blade above said discs 45 and having its upper end curved forwardly and connected to a pivotal support, and means to move said blade forwardly and downwardly, the lower end of said blade being concaved to conform to the curvature of
50 said discs.

12. In combination with a cotton gin having gin saws therein, means co-acting with said saws to separate the cotton lint from the seed, and a doffer plate above said saws 55 to assist the saws in imparting a rotative movement to the cotton.

13. In combination with a cotton gin having gin saws therein, means co-acting with said saws to separate the cotton lint from the seed and means to prevent the passage 60 of cotton above said saws and to assist said saws in the rotation of the cotton above the saws.

14. In combination with a cotton gin hav-
65 ing gin saws therein, means co-acting with

said saws to separate the cotton lint from the seed, and a doffer plate above said saws to assist the saws in imparting a rotative movement to the cotton and means to move said plate downwardly forwardly and upwardly 70 to impart a rotative movement to the cotton roll in front of said saws.

In testimony whereof I hereunto affix my signature this 23d day of September, A. D. 1929.

HOY OWEN.
